UNITED STATES PATENT OFFICE.

MORITZ KIRCHBERGER, OF NEW YORK, N. Y.

DESIGN FOR A GAS-BURNER PILLAR.

41,659.

Specification for Design.

Patented Aug. 8, 1911.

Application filed December 5, 1910. Serial No. 595,794. Term of patent 7 years.

To all whom it may concern:

Be it known that I, MORITZ KIRCHBERGER, a citizen of the United States, residing in the city, county, and State of New York, have invented a new, original, and ornamental Design for a Gas-Burner Pillar, of which the following is a specification, reference being had to the accompanying drawing, forming part thereof, and in which—

Figure 1 is a side view showing a gas burner pillar incorporating my design. Fig. 2 is a top view of the same.

I claim:

The ornamental design for a gas burner pillar as shown.

In testimony whereof I have signed this specification in the presence of two subscribing witnesses.

MORITZ KIRCHBERGER.

Witnesses:

STELLA E. WITT,
ROSE JACOBY.
